HACK SAW FRAME

John H. Dohner, Robinson, Kans.

Application August 14, 1947, Serial No. 768,548

3 Claims. (Cl. 145—34)

1

This invention relates to hand tools, and more particularly to hacksaws, especially those adapted for heavy duty work.

The primary object of the invention is to provide a hacksaw of a novel and improved construction which, while clearly adapted for the performance of any of the ordinary types of work, has embodied in it a tension adjustment means that is particularly adapted to withstand the strain imposed in heavy work.

It is a further important object of the invention to provide a novel and improved tension adjustment means which, though simple and capable of being operated in a minimum of time, is nevertheless adapted for the effecting of tension adjustments to an unusually fine extent.

Still another object of the invention is to provide economy of manufacture in such a tool, even considering its special capabilities as mentioned above, by devising a tool having a minimum of parts simply arranged.

Still another object of the invention is to provide in a tool of the type stated an improved blade bearing means that will permit easy and speedy attachment or removal of a blade, is specially adapted to prevent a blade from falling from the frame when tension is relaxed, and which will at all times hold the blade in fixed and exact alignment with the rest of the frame.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing:

Figure 1 is a side elevational view of a hacksaw frame constructed in accordance with the invention, a portion being broken away to show details of construction.

Figure 2 is a top plan view.

Figure 3 is a view on an enlarged scale, partly in side elevation and partly in longitudinal section, taken through the handle portion of the frame, a fragmentary part of the frame proper being also shown, in side elevation.

Figure 4 is a view taken on line 4—4 of Figure 1.

Figure 5 is a view taken on line 5—5 of Figure 1.

Referring to the drawing in detail, the reference character 5 designates generally the outer frame section, being of L-shaped formation, having a back 6 and an arm 7 extended from one end thereof.

2

The inner section of the frame comprises an arm 8 rigid with a back 9 of flattened and sleeve-like formation, the back 6 of the L member being telescopically received therein.

Permanently and rigidly joined, as by welding or the like, to the arm 8 is a hollow member 10, one end of which may be slotted inwardly for the purpose of receiving the arm 8 and making the said connection. This member constitutes an inner barrel or tubular spindle, and can be termed part of the inner frame section.

Referring particularly to Figure 3, the other end of the inner barrel 10 is exteriorly threaded, and these threads may be coarse for the purpose of permitting quick preliminary adjustment in a manner to be described hereinafter. The threaded end 11 is open, and a spring 12 normally held under compression is extended through the opening, the inner end thereof abutting against the arm 8.

The handle for the hacksaw is designated at 13, and preferably is of the pistol-grip type, knurled to permit a sure grip thereon. Fixedly connected to the grip is a guard 14 for the usual well-known purpose.

The upper end of the handle 13 is formed as an outer barrel 15, the inner end of which is reduced as at 16 and is open to permit entry of the inner barrel. Rigid with said inner end 16 and outer barrel 15 is a cam disc 17, disposed in a plane substantially perpendicular to the common axis of barrels 10 and 15. The face of the cam disc 17 that confronts the telescoping sections of the frame is annularly inclined, a suitable distance around the periphery of the disc.

Positioned in the outer barrel 15 is a spacer sleeve 18, which is somewhat shorter than the outer barrel, and which may be either fixedly mounted within the outer barrel or made simply insertible therein, the inner end thereof abutting against the shoulder defined by provision of the reduced end 16 of the outer barrel, as clearly shown in Figure 3. The inner barrel 10 of the frame section slides in the spacer sleeve 18.

45 Abutting against the other end of spacer sleeve 18, and also carried within the outer barrel 15, is a washer 18' of like diameter with the spacer sleeve.

An adjusting sleeve is designated at 19, this being slidable relative to the outer barrel 15, in the open outer end of which it is inserted. The projecting end of the adjusting sleeve is closed as at 20, and the outer end of spring 12 abuts thereagainst.

55 The inner end of the adjusting sleeve 19 en-

gages the washer 18' as clearly shown in Figure 3.

The back 6 of the outer frame section 5 is, as clearly shown in Figure 1, formed with a plurality of spaced notches 21, in any of which cam disc 17 can be engaged. These notches are selected for engagement with the cam disc according to the length of a blade B to be carried by the frame.

Formed in the thinnest part of the cam disc 17, for receiving the back 6, is a notch 22. From this, it is seen that if the user partially rotates the handle portion of the hack saw relative to the outer frame section 5 thereof, notch 22 can be presented to the back 6, so that the back 6 may be adjusted in either direction until the desired notch 21 thereof is positioned for engagement by the cam disc. Returning of the handle portion of the device to its normal position when results in engagement of the cam disc in the notch 21, and such return results in the thickest portion of the disc being engaged in the notch, when the handle portion is fully returned to its normal position. Further movement in the same direction is limited by lugs 23 projected from opposite sides of the cam disc 17.

It is to be noted at this point, and referring particularly to Figure 1 or 3, that the thickest portion of the cam disc used in regulator operation of the device for the purposes stated is nevertheless of smaller width than any of the notches 21. Other portions of the disc, not used in normal operation of the device in effecting tension adjustment may be thickened or inclined forwardly as desired, this being for the purpose of preventing fully free rotation of the handle portion of the frame.

At 24 is shown a shallow indentation formed in the inclined face of the cam disc, this being formed immediately adjacent lugs 23, as clearly shown in Figure 4. This serves as a locking indentation, in a manner to be described herein-after.

Referring now to the means embodied in the invention for attaching the blade B, the free ends of arms 7 and 8 are enlarged as at 25, and have inwardly extended portions 26 projected toward each other. In each of the portions 26 is formed a relatively large opening 27, with which communicates a closed slot 28 of sufficient length and width to receive the end of blade B. Between enlargement 25 and opening 27 is formed another and smaller opening 29, and communicating with this opening is a recess 30 receiving coil spring 31.

A broken ring 32 is carried in the openings 27 and 29, and ordinarily is freely rotatable therein. Spring 31 at one end engages ring 32, and continually urges it inwardly.

It is thus seen that if it is desired to attach a blade B, the end of the blade is inserted through slot 28 so as to project into the opening 27. Before doing so, however, ring 32 is rotated so that the open part thereof is positioned against the slot 28, thus permitting entry of blade B. When the blade has been inserted a sufficient extent so that the usual opening therein presents itself to the ends of the ring, the ring 32 is rotated a sufficient extent, so as to preferably assume the position shown in Figure 5. It may be observed that even though no tension has been placed upon the frame, the spring 31 engaging each of the rings 32 will prevent movement thereof except upon the exertion of a positive manual pressure to rotate the ring.

In the use of the hack saw constructed in accordance with the invention, the handle portion

is partially rotated relative to the telescoping frame sections, so that notch 22 is presented to back 6. This permits free movement of the frame sections relative to each other, and a blade B of desired length is then selected and attached as previously described. The desired notch 21 will by this operation have been presented to cam disc 17. The basic adjustment for length of the frame is accordingly made, and there is now effected a preliminary tension adjustment.

This is made by threading the adjusting sleeve 19 forwardly, while the handle portion is still in offset position relative to the rest of the frame. When the adjusting sleeve is threaded forwardly in this manner, it will be seen that it will carry with it the handle portion of the device, having thereon cam disc 17, these being thus adjusted forwardly relative to the outer and inner frame sections.

When the adjusting sleeve has been threaded forward a desired distance, the handle section of the device is returned to its normal position, and in doing so, the L member 5 will be pressed away from the inner frame section, placing a strong tension upon the blade B. When the handle section has been fully returned to its normal position, the shallow indentation 24 will engage in notch 21, or more properly one wall thereof, with the parts thus being locked in desired position and under suitable tension.

Mention is here made of spring 12. While this spring is not essential to the operation of the invention, it is preferred to use it particularly where a quick thread connection is employed between the inner barrel 10 and adjusting sleeve 19, since the spring 12 can thus at all times urge the connected members away from each other in the event of any looseness in the connection, particularly after long operation of the device.

Particular importance is placed upon the ease of operation in effecting a proper tension adjustment, wherein the user is required to make only a preliminary adjustment, the extent of which is capable of being visually determined, or by trying the cam disc against the wall of notch 21. Having threaded the outer barrel 15 carrying cam disc 17 forwardly in making this rough adjustment, it is only necessary to swing the handle back into normal position, this action automatically placing the whole frame under strong tension and locking the parts together.

What is claimed is:

1. In a hack saw relatively slidable inner and outer frame sections, the outer section having a back portion formed with notches spaced longitudinally thereof; a blade connected at opposite ends to the respective sections; a spindle rigid at one end with and extending away from the inner frame section in parallelism with and below said back portion; an outer barrel mounted on the spindle for rotation and for sliding movement longitudinally of the spindle; a handle rigid with and extending laterally from the outer barrel; a cam disc having an inclined face rigid with and surrounding the outer barrel, said disc being engageable in any of said notches; and means movably mounted on said spindle and engageable with the barrel to shift the barrel slidably and longitudinally of the spindle, whereby to transmit slidable movement to the outer frame section through the medium of the cam disc and notch engagement for preliminary tensioning of the blade, the handle and barrel being rotatable in the position to which the barrel is slidably

moved for camming engagement of the inclined face of the disc with the wall of the notch whereby to impart additional sliding movement to said outer frame section and effect final tensioning of the blade.

2. In a hack saw relatively slidable inner and outer frame sections, the outer section having a back portion formed with notches spaced longitudinally thereof; a blade connected at opposite ends to the respective sections; a spindle rigid at one end with and extending away from the inner frame section in parallelism with and below said back portion, the other end of the spindle being threaded; an outer barrel mounted on the spindle for rotation and for sliding movement longitudinally of the spindle; a handle rigid with and extending laterally from the outer barrel; a cam disc having an inclined face rigid with and surrounding the outer barrel, said disc being engageable in any of said notches; and an adjusting sleeve threaded on the spindle and engaging the barrel to shift the barrel slidably and longitudinally of the spindle whereby to transmit slidable movement to the outer frame section through the medium of the cam disc and notch engagement for preliminary tensioning of the blade, the handle and barrel being rotatable in the position to which the outer barrel is slidably moved for camming engagement of the inclined face of the disc with the wall of the notch whereby to impart additional sliding movement to said outer frame section and effect final tensioning of the blade.

3. A hack saw comprising an inner frame section; a sleeve formed thereon; an outer frame section having a back portion slidable in the sleeve, there being a plurality of widely spaced notches formed in and disposed longitudinally of said back portion; a blade connected at opposite ends to the respective frame sections; a spindle rigid at one end with and extending away from the inner frame section in parallelism with and below said back portion, the other end of the

spindle being threaded, the spindle having a smooth-surfaced medial portion; a spacer sleeve mounted on the medial portion of the spindle to slide longitudinally thereof; an outer barrel mounted rotatably on the spacer sleeve and having a shoulder engaged by one end of the spacer sleeve to shift the barrel longitudinally of the spindle with the spacer sleeve; a handle rigid with and extending laterally from the outer barrel; a cam disc having an inclined face rigid with and surrounding the outer barrel, said disc being engageable in any of said notches; and an adjusting sleeve threaded on the threaded end of the spindle and engaging the other end of the spacer sleeve to shift the spacer sleeve longitudinally of the spindle, whereby to transmit slidable movement to the outer frame section through the medium of the cam disc and notch engagement for preliminary tensioning of the blade, the handle and barrel being rotatable in the position to which the barrel is slidably moved, for camming engagement of the inclined face of the disc against the wall of the notch, whereby to impart additional sliding movement to the outer frame section and effect final tensioning of the blade.
